STAPLING MECHANISM

Fred A. Scherman, Racine, Wis., assignor to Ajax
Tool and Die Company, Racine, Wis., a corpora-
tion of Wisconsin

Application October 21, 1938, Serial No. 236,178

4 Claims. (Cl. 1—3)

This invention relates to improvements in stapling mechanism.

It is the primary object of the invention to provide a novel and simplified type of stapler which can readily be manufactured of simple stampings, requiring few parts, providing substantially complete enclosure for the operating mechanism, and avoiding any possibility of stoppage.

The construction is such that the detailed organization of parts is highly significant to the general objectives as above stated, and accordingly further objects of the invention will be found in the following disclosure.

In the drawings:

Fig. 1 is a perspective view of the assembled apparatus.

Fig. 2 is a view of the apparatus in longitudinal section.

Fig. 3 is a view taken in transverse section on the line 3—3 of Fig. 2.

Fig. 4 is a view taken in transverse section on the line 4—4 of Fig. 2.

Fig. 5 is a fragmentary bottom plan view of the stapling head as viewed on the line 5—5 of Fig. 2.

Fig. 6 is a view showing in perspective the several component parts of the device, with the exception of one of the casing elements, as such parts appear when separated preparatory to assembly.

Fig. 7 is a detail view in perspective showing the staple slide follower.

Like parts are identified by the same reference characters throughout the several views.

As the description proceeds, attention should be given to the manner in which the several stampings comprising the frame and casing of the stapler are each designed to perform a variety of functions so as to minimize the number of parts and reduce assembly costs.

The base 8 comprises a shallow box-like stamping marginally provided at 9 with a flange which is preferably engaged by the complementary flange of a shoe 10 of rubber or the like.

A shallow recess at 11 assists in positioning the clinching die 12 which is of generally conventional form. Upstanding ears 15 formed integrally from the material of the base serve to support the pintle bolt 16 upon which the stapling head oscillates on to the thrust of a leaf spring 17 of the cantilever type which is provided at 18 with an aperture engaged by a tongue 19 formed integrally from the base. The tongue 19 projects into an opening 20 in the base which receives the end of the spring. The spring ful-

crums across the forward edge 21 of the portion of the base adjacent opening 20.

The central structural member of the oscillating stapling head comprises an inverted channel 25 having sides provided with shouldered offsets at 26 and terminating in marginal flanges 27. The flanges 27 serve as spacers for the stamped sides 28 and 29 which have downwardly extending ears 30 apertured at 300 to receive the pintle 16, whereby the stapling head is tiltably mounted. The sides 28 and 29 (Figures 2 and 6) and intervening channel 25 are connected by rivets 31, 32 and 33. At a level above the channel 25 the sides are also connected by a bridge member 35 which has integral tongues 36 extended through suitable apertures 360 in the sides and there upset or riveted to connect the sides together. Bridge member 35 is, like the base 8, provided with an anchorage for a cantilever spring which is shown at 37. This spring fulcrums on the edge 38 of the bridge member adjacent an opening 39 therein into which the tongue 40 projects to engage the opening 41 in the end of the spring. Spring 37 supports the stapling plunger as will hereinafter be described. It is a stronger spring than spring 17.

Extending longitudinally of the two sides 28 and 29 are inwardly turned flanges 42 and 43 respectively, which overlie the top of the inverted channel 25 in spaced relation thereto. The sides of the channel, above shoulders 26, are also in spaced relation to the sides of the members 28 and 29. There is thus provided about the upper side and top portions of channel 25 a guide slot of such dimensions as to be adapted to receive the preformed stick of staples 45 as best shown in Fig. 3. Also receivable into the guide slot is the follower 46 which has a cross section similar to that of the staples, and has an upstanding lug 47 traveling between the margins of the inwardly directed flanges 42 and 43. The ears 48 and 49 on the follower 46 are engaged by a rod 50 encircled by a light compression spring 51 and provided at its end with a hook 52 releasably engageable in the opening 53 of the channel as shown in Fig. 2. The follower is free to slide on rod 50 to transmit to the staples 45 the pressure of the spring 51 which impels the staples successively to the drive slot.

The side frame members 28 and 29 of the stapling head are connected at their forward ends by a front member 54 which is riveted thereto by rivets 31, 55 and 56 (see Fig. 2 and Fig. 5). The front wall 57 of the member 54 tightly abuts the front margins of the side frame

elements 28 and 29 but is spaced forwardly from the end of channel 25 to provide a feed throat at 60 (Fig. 2 and Fig. 5) through which successive staples are forced by the driving slide hereinafter to be described.

The front wall 57 is centrally notched at 61 as shown in Fig. 1, Fig. 2 and Fig. 4, to receive spring 62 which is secured to the outer surface of wall 57 and extends first forwardly therefrom and then back upon itself through the slot 61 to a position normally underlying the top of channel 25 (Figs. 2 and 5). This spring is gradually forced forwardly out of the way by a staple impelled downwardly through the guideway 60, but the staple does not clear the spring until it is substantially fully engaged with the work. If the pressure on the staple is released before the staple is engaged with the work, the staple will be retracted by spring 62 with the feed slide, thereby preventing clogging of the guideway.

The feed slide or driver 63 is vertically reciprocable in the guideway 60 and is connected with a manually operable spring supported plunger 64 for its actuation. A rivet 65 (Fig. 2), serves as one means of connection of the slide to the plunger. The front wall 57 of the front plate 54 is channeled at 66 to accommodate the movement of the rivet.

The plunger may conveniently be made from a single stamping folded into a hollow oblong form as shown in Fig. 2 and Fig. 6. Its sides are slotted at 67 to receive the transverse bolt 670 upon which the lower end of the plunger is guided. The free margins of the stamping constituting plunger 64 are provided with corresponding upwardly extending lugs at 68, both of which are together received through the stamped opening 69 in the pressure plate 70. A wider opening 71 near the forward margin of plate 70 receives the lug 72 of the plunger stamping 64, and also receives the lug 73 at the upper end of the drive slide 63. The lug 72 on the plunger stamping is slightly longer than lug 73 on the driver slide to enable it to be upset or riveted over the surface of plate 70, the same procedure being followed with lug 68. The upsetting of lug 72 wedges lug 73 of the driver slide rigidly into unitary connection with the pressure plate 70. The lug of the driver slide is not upset because this slide is usually made of hard material.

An opening at 74 in the back of the tubular plunger 64 receives the end of the spring 37 whereby the plunger is normally supported in the raised position in which it is illustrated in the drawings. Pressure plate 70 is preferably covered with a rubber cap 75 applied in the same manner that the rubber shoe 10 is applied to the base of the instrument.

The entire tilting stapling head is preferably encased in a two part housing which tilts therewith and is readily removable. The housing elements 76 and 77 each comprise hollow box-like stampings having their side flanges in marginal abutment on the vertical longitudinal center line of the apparatus. The bolt 670 which guides plunger 64 extends through the sides of this case to connect such sides at the forward end of the apparatus. Their only other means of connection is the pivot bolt 16 upon which the stapling head pivots. This also extends through the case and serves to connect the parts 76 and 77 thereof together.

There are only three exposed openings through the case. The spring 62 which prevents clogging projects through a notch at 78 in the front end

of the case. The rod 50 which serves as a guide for the compression spring of the staple follower projects through an opening at 79 in the rear end of the case. The plunger 64 projects upwardly through an opening 80 at the top of the case and is guided by the case for vertical reciprocation. Thus the case performs a mechanical function of the device as well as concealing the mechanism and thereby beautifying the entire assembly.

The staples used are inserted and fed through the feed slot under the pressure of spring 51 in much the usual manner. When the work is inserted beneath the stapling head on the clinching anvil 12 the pad 75 on the pressure plate 70 is struck to impel the driving slide 63 downwardly, thus forcing the foremost staple down through the drive slot 60 into engagement with the work. Since the spring 17 is weaker than spring 37, the initial pressure on the plunger will first tilt the stapling head into engagement with the work, following which the driving action will occur as described.

I am aware that there are other stapling devices which are made partially or principally of stampings, but the present device can be made more cheaply than any other with which I am familiar because of the way in which the stampings are formed and the manner in which they co-act.

I claim:

1. In a device of the character described, the combination with a base provided with an aperture and having a tongue projecting into the aperture, of a leaf spring fulcrumed across the top of the base adjacent the aperture and remote from the tongue and provided with an opening in which said tongue is engaged for releasably securing said spring against displacement, a stapling head pivotally connected with the base for limited movement with respect thereto and provided with a part engaged by the end of said spring remote from said base, the limit of movement of said head and the point of engagement of said spring therewith being such as to urge said head toward one extreme of its movement and to maintain said spring under slight initial deflection at such extreme.

2. In a device of the character described, a stapling head comprising side plates and an inverted channel connecting said side plates and provided at its top with a transverse web having an opening therewithin, said channel having marginal flanges connected with the side plates and offset to provide a staple guideway between said plates and web, a follower movable in the guideway, a guide rod upon which said follower is slidable, said rod being disposed between said plates and above said web, spring means on said rod, and a reversely curved hook at the end of said rod extending about said web and engaged with the opening therein from beneath for maintaining said rod in position and sustaining the compression of said spring.

3. In a device of the character described, a stapler head frame comprising a pair of side plates, a plunger, means guiding said plunger for reciprocation between said plates, means connecting said plates comprising a spring anchorage, and a leaf spring engaged in said anchorage and having an end in supporting relation to said plunger.

4. In a device of the character described, a stapling head comprising a pair of side plates

having apertures, a connecting web having tongues extending through said apertures and riveted upon said plates to maintain their assembly, said web having a central opening and a finger projecting into said opening, a plunger reciproicable between said plates, means for guiding said plunger for reciprocation, a leaf spring

having a free end engaged with said plunger and provided with an opening in which said finger is engaged, said spring being fulcrumed over the edge of said web adjacent the opening therein, whereby said spring has a cantilever mounting on said frame.

FRED A. SCHERMAN.
